SEAM RIPPER

Herman Ament, 60 Marbledale Road,
Tuckahoe, N.Y. 10707

Filed Jan. 21, 1966, Ser. No. 717

Term of patent 14 years

(Cl. D95—1)

FIG. 1 is a front perspective view of a seam ripper showing my new design.

FIG. 2 is an end perspective view thereof.

FIG. 3 is a perspective view of the end thereof opposite that shown in FIG. 2.

The cap for the seam ripper has been omitted from FIGS. 2 and 3 for convenience of illustration.

The essential features of my new design reside in the particular handle and cap portions having a flattened hexagonal configuration with opposite planar faces wider than angularly disposed side surfaces, the handle having flat tapers at opposite ends and the cap being tapered to fit on either tapered end of the handle.

I claim:

The ornamental design for a seam ripper as shown and described.
